TYPEWRITING MACHINE

Henry J. Hart, West Hartford, Conn., assignor
to Royal Typewriter Company, Inc., New York,
N. Y., a corporation of New York

Application October 25, 1935, Serial No. 46,814

4 Claims. (Cl. 197—183)

This invention relates to new and useful improvements in typewriting machines generally, although more particularly to abutments or anvils for the type bars.

The principal objects of the invention are to provide an abutment which will reduce the noise made by a type bar connecting the same, and to provide means for easily assembling the abutment and the segment guard plate on the segment, or removing the same therefrom.

With these and other objects in view which will more fully appear, the nature of the invention will be more clearly understood by following the description, the appended claims, and the several views illustrated in the accompanying drawing.

In the drawing:

Figure 1 is a front elevation of a type bar segment constructed in accordance with my invention,

Figure 2 is a top plan view thereof,

Figure 3 is a perspective view of the segment,

Figure 4 is a perspective view of the abutment,

Figure 5 is a detail cross-sectional view taken on the line 5—5 of Figure 1, and

Figure 6 is an enlarged cross sectional view of the abutment.

Referring to the accompanying drawing, the segment A is formed along its lower portion with the usual radially extending slots 5 for receiving the heels of type bars 6 which are pivoted on the wire 7. The central portion of the segment A above the type bar pivots is formed with an arcuate recess 8, and partially extending into this recess is a vertical web or wall 9 which is spaced rearwardly from the front face of the segment to form a resultant arcuate seat 10 located directly above the slots 5, said seat including an arcuate groove 11 formed in the front face of the web 9 and an arcuate undercut or inclined lateral wall 12 which is disposed directly in front of the web and merges with the lower edge of the groove 11. Attached to the rear face of the web 9 by screws 13 is the usual sheet metal type bar guide 14.

An arcuate abutment B of sound-deadening and wear-resisting construction is received in the groove 11 of the seat 10, the outer periphery 15 of the abutment being transversely inclined to fit the inclined lateral wall 12 of the seat.

This abutment comprises a laminated structure consisting of a plurality of thin metallic arcuate laminae or plates 16, preferably of spring steel, which are rigidly secured together by rivets 17 located at spaced intervals throughout the length

of the abutment. The depth of the groove 11 is equal to the thickness of the rearmost plate 16, and integral with the next adjacent plate are inwardly extending attaching ears 18, 18 which lie flush against the front face of the web 9. 5 Screws 19, 19 pass through the ears 18, 18 and are engageable in threaded openings 20, 20 located in the web 9. The most forwardly disposed plate 16 constitutes a front striker plate whose outer face is disposed in advance of the front face 10 of the segment so as to be engaged by the type bars when the latter are swung upwardly to print, as shown in Figure 5.

It is well known that surfaces generally considered perfectly flat are not perfect planes, and 15 that when such surfaces are opposed one to the other air pockets intervene. It will be obvious therefore that when a multiplicity of thin spring steel plates are assembled face to face to form an abutment pack as shown in Figures 4 and 6 20 of the drawing, microscopic air pockets exist between the opposed surfaces of the plates and serve to deaden the sound of type bar impacts.

The equidistant spacing of the assembling rivets 17 contributes to the uniformity of the relation between the respective plates 16 constituting the abutment pack. It will be noted also that the plate equipped with the ears 18 constitutes a 25 mounting plate and that the remainder of the plates are held on the mounting plate as and for 30 the purposes stated.

A sheet metal guard plate 21 for the recess 8 is positioned against the front face of the web 9 and overlies the ears 18 of the abutment B. The plate is secured to the web by the screws 19, 35 the lower edge of the plate being arcuate and lying directly above and in abutting relation to the upper arcuate surface of the abutment B.

From the foregoing, it will be seen that I have provided an abutment of sound-deadening and 40 wear-resisting construction; that the abutment can be readily applied to or removed from the segment, and when in operative position the abutment is firmly seated throughout its entire length and consequently the abutment will react 45 uniformly to the impacts of all the type bars.

I claim:

1. A self-contained laminated abutment for typewriter type bars adapted to be attached as a unit to and detached as a unit from a type bar 50 segment, said abutment comprising a plurality of flat thin arcuate metallic plates; means extending between the outermost plates and through the intermediate plates for securing said plates together irrespective of whether the abut- 55

- ment is attached to or detached from the segment; and means for attaching the abutment to the segment.
2. In a typewriting machine, the combination with type bars and a segment on which they are pivoted; of an assembled laminated abutment for said type bars adapted to be attached as a unit to said segment and detached as unit from said segment, said abutment in itself comprising a multiplicity of laminae, a metal facing plate, a rear plate, connecting means extending between said facing plate and said rear plate and passing through intervening laminae, said facing plate, rear plate, and connecting means holding said laminae together, and there being cushioning air films between the laminae; and means independent of said connecting means for detachably mounting said abutment as a unit on said segment.
3. In a typewriting machine, the combination with type bars and a segment on which they are pivoted; of an assembled laminated abutment for said type bars adapted to be attached as a unit to said segment and detached as a unit from said segment, said abutment in itself comprising a multiplicity of laminae, a metal facing plate, a

rear plate, rivets extending between said facing plate and said rear plate and passing through intervening laminae, said facing plate, rear plate, and rivets holding said laminae together, and there being cushioning air films between the laminae; and means independent of said rivets for detachably mounting said abutment as a unit on said segment.

4. In a typewriting machine, the combination with type bars and a segment to which the type bars are pivoted, said segment above the type bar pivots being formed with a seat comprising an arcuate groove located in the front face of the segment and a forwardly disposed arcuate lateral wall merging with the lower edge of said groove, an arcuate abutment for the type bars mounted in said seat, said abutment comprising a laminated structure consisting of a plurality of metallic plates rigidly secured together, the depth of the groove being equal to the thickness of the rearmost plate, attaching ears integral with the next adjacent plate and extending inwardly therefrom, and screws passing through the ears and having threadable engagement with the segment.

HENRY J. HART.
